UNITED STATES PATENT OFFICE.

MAXIMILLIAN H. SPIELMAN, OF NEW YORK, N. Y.

ELECTRIC CIGAR-LIGHTER.

1,164,767.

Specification of Letters Patent. Patented Dec. 21, 1915.

Application filed July 26, 1915. Serial No. 41,833.

To all whom it may concern:

Be it known that I, MAXIMILLIAN H. SPIELMAN, a citizen of the United States, and a resident of the borough of Manhattan, city, county, and State of New York, have invented certain new and useful Improvements in Electric Cigar-Lighters, of which the following is a description in such full, clear, and exact terms as will enable 10 any person skilled in the art to which it pertains to make and use the same.

The invention relates to a cigar lighter of that class in which a fine metallic wire is heated to incandescence by electricity to enable 15 the cigar to be lighted therefrom. Ordinarily these devices operate with difficulty because the smoker cannot draw air through the cigar when it is engaged with the lighter and difficulty is thereby experienced in setting 20 fire to the cigar.

The object of my invention is to overcome this difficulty by providing for a movement of an air current through the cigar lighter, while, and by reason of puffing on the cigar.

Reference is now had to the accompanying drawings which show as an example the preferred embodiment of my invention.

In these drawings—Figure 1 is a sectional elevation of the cigar lighter and Fig. 2 is 30 a detail section showing the preferred manner of fastening the incandescent wires.

The device is provided with a body *a* of metal or other suitable material furnished with a switch *a'* to be operated with the 35 thumb or other finger of the user while holding the device. The current is carried to the body *a* preferably by flexible wires *b* which terminate in contact points *b'* at the upper part of the body.

40 The cap of the device in which my invention resides is formed preferably of a cylindrical metal outer part *c* and of cylindrical metal inner part *d* swaged together at their outer ends and separated from each 45 other at their inner ends so that the body *a* may lock with the cap through the action of a pin and bayonet slot device *e*. The outer part *c* of the cap is separated from the body *a* so that air currents may pass 50 between them and the inner part *d* has openings *d'* which allow the air to enter the interior of the cap.

A suitable mica or other insulation disk *f* is fastened in the outer part of the cap and

has a number of orifices *f'* therein which 55 serve the double purpose of allowing the incandescent wire *g* to be woven through them and allowing the air currents before mentioned to pass. The wires *g* extend down to contact points *h* held in the inner 60 portion of the cap by an insulation mass *h'* which is secured in the part *d*.

The incandescent wire may be secured to the insulation head or disk *f* of the cap in any way desired but I prefer to employ the 65 clasps *h* shown in Fig. 2, which are made of wire and pass around the incandescent wire *g*, the inner ends of the clasps being bent to anchor them in place. This prevents the user from displacing the incandescent wires 70 by rubbing the end of the cigar against them. Of course, the incandescent wire is projected out in a number of ramifications over the face of the disk or head plate *f* so as to present a larger surface to the cigar 75 and to facilitate the lighting thereof.

In the use of my invention the user takes the device in his hand and closes the electric circuit by operating the switch *a'*. This raises the wire *g* to incandescence and the 80 cigar may be lighted by placing the end of the cigar against the wire and puffing or drawing on the cigar which induces a current of air under the part *c* of the head of the device, through the holes *d'* and *f'* and 85 into the cigar and allows the cigar to be easily lighted.

Having thus described my invention, what I claim as new and desire to secure by Letters Patent of the United States is:—

An electrical cigar lighter having a body with an open end, a cap set removably on the said end of the body and comprising spaced cylindrical inner and outer side parts, the inner being orificed and engaging 95 the body and the outer spaced from the body for the circulation of the air through it to the orifice of the inner wall, an orificed insulation disk in the outer part of the cap and complementary electrical conductor 100 means on said disk, for the purpose specified.

In testimony whereof I have hereunto signed my name in the presence of two witnesses.

MAXIMILLIAN H. SPIELMAN.

Witnesses:

PATRICK A. BOLGER,
S. E. TANNER.
